UNITED STATES PATENT OFFICE.

BERTON E. COOK, OF CHICAGO, ILLINOIS.

HAND-OPERATED LATCH NEEDLE.

Application filed July 30, 1928. Serial No. 296,347.

My invention relates to improvements in hand-operated latch needles, and it consists in the combinations, constructions, and arrangements herein described and claimed.

5 An object of my invention is to provide a hand-operated latch-needle in which means is provided whereby the device is rendered certain in operation.

10 A further object is to provide a hand-operated latch needle in which spring means is provided for guiding the device during operation.

15 A further object is to provide a hand-operated latch needle in which means is provided for releasing the latch in the event that the latch should become locked, thereby insuring accuracy in operation.

20 Other objects and advantages will appear in the following specification, and the novel features of the invention will be particularly pointed out in the appended claims.

25 My invention is illustrated in the accompanying drawings, forming part of this application, in which

Figure 1 is a perspective view of my device,

Figure 2 is an elevation of the device shown in Figure 1,

30 Figure 3 is an elevation of the device shown in Figure 2 turned 90°, and

Figure 4 is a view showing an application of the device.

35 In carrying out my invention, I make use of a handle 1 of any suitable shape adapted to support a needle 2 bent to form a stop 3. The needle 2 is provided with a hooked portion 4 and a latch 5 hinged at 6.

40 A flexible spring member 7 is secured to the handle 1 and is bent double at 8 to provide a slotted member 9. The needle 2 passes through the slot and the member 9 is adapted to be moved relative to the needle from the full line position into the dotted line position shown in Figure 3. Movement of the member 9 is limited by reason of the stop 3. During the operation of the device, that is, when the needle is passed through the fabric, a thread will pass between the latch 5 and the hooked portion 4 moving the latch

50 5 into the position shown in Figure 2. At this time, the slotted member 9 will be moved in contact with the stop 3. The slotted member 9 acts as a guide for the device when the needle is passed through the fabric, thus limiting the distance which the needle may be moved through the fabric. When the

latch 5 is in the position shown in Figure 2, a space 10 is provided between the latch and the slotted member 9. The space is such that a thread may be moved therein and between the latch and the needle 2. When the needle has been passed through the fabric and is removed therefrom, the spring-pressed member 9 will of course move back to its original position. It will be seen from Figure 65 2 that should the latch 5 become locked or bind, the member 9 will dislodge the latch, thereby insuring the operation of the device.

It will thus be seen that I have provided a needle which is easy to manipulate in that a 70 guide 9 is provided. With this provision, a hand-operated needle may be operated rapidly and with a maximum degree of certainty.

While I have stated that the spring member 7 is secured to the handle 1, the spring 75 member 7 is preferably soldered to the needle or secured thereto by other desirable means, and the handle 1 serves as a support for the needle and also the spring.

I claim:

1. In a hand-operated latch needle having a handle, spring means secured to the handle and associated with the needle for limiting the movement of the needle when the latter is passed through a fabric.

2. A hand-operated latch needle comprising a handle portion, a latch needle secured to the handle, and flexible means secured to the handle and disposed in operative relation with respect to the needle and adapted to be flexed by contact with a fabric for guiding and limiting the movement of the needle when the latter is projected through the fabric.

3. A hand-operated latch needle comprising a handle, a latch needle secured to the handle, spring means secured to the handle and disposed in operative relation with respect to the needle and adapted to be flexed when moved into engagement with a fabric 95 for guiding and limiting the movement of the latter when the needle is projected through the fabric, and means secured to the handle for stopping the movement of said spring means.

4. A hand-operated latch needle comprising a handle, a needle secured to the handle, and spring means secured to the handle and disposed in operative relation with respect to the needle and adapted to be moved by contacting with a fabric for limiting the movement of said needle when the latter is pro-

jected through the fabric, said needle being provided with a stop for limiting the movement of said spring means, said needle being provided with a latch adapted to be moved 5 for bringing one end of said latch relatively near a portion of said spring means, whereby said spring means is adapted to move said

latch in the direction of its original position when said latch needle is removed from the fabric.

Signed at Chicago, in the county of Cook and State of Illinois this 25th day of July, A. D. 1928.

BERTON E. COOK.
